UNITED STATES PATENT OFFICE.

JACOB W. GREENE, OF CHILlicothe, Missouri, ASSIGNOR TO DETROIT DENTAL MANUFACTURING COMPANY, OF DETROIT, MICHIGAN, A CORPORATION OF MICHIGAN.

DENTAL IMPRESSION-TRAY.

987,063.

Specification of Letters Patent. Patented Mar. 14, 1911.

Application filed May 12, 1910. Serial No. 560,953.

To all whom it may concern:

Be it known that I, JACOB W. GREENE, a citizen of the United States, residing at Chillicothe, in the county of Livingston and State of Missouri, have invented certain new and useful Improvements in Dental Impression-Trays; and I do hereby declare the following to be a full, clear, and exact description of the invention, such as will enable others skilled in the art to which it appertains to make and use the same.

My invention relates to dental impression trays for taking impressions of the mouth for making artificial dentures.

15 The ordinary trays in common use have long heavy and cumbersome stationary handles which are in the way and prevent the accomplishment of some of the most important purposes of an impression. One of 20 these purposes is to get an exact fit to the moving muscles of the mouth so that the denture, when made, will allow the muscles to act freely and yet preserve the requisite valve-like air-tight pressure. In other 25 words, it is desired to relieve the pressure of the denture upon the moving muscles without causing a leak which would loosen the denture in the mouth. This exact fit of the impression material to the moving muscles 30 can only be made with exactness and certainty by the active movement of said muscles themselves. All other methods of getting such a fit are guess work, such as by filing and cutting, and are very uncertain. To 35 assist in the edge trimming of the impression material by the muscles themselves, the edge of the material may be warmed and thus made more susceptible to impressions. The patient then works his lips and cheeks 40 vigorously which causes the moving muscles to cut their way down into the edge of the impression material thereby making the proper and exact form needed for the denture plate which is to be made from the im- 45 pression. Another modern up-to-date purpose in an impression tray is to get not only the fit to the mouth but also the fullness of the patient's features on the impression. This is done also by the movement of the 50 lips and cheeks, the edges of the impression material being first made a little too prominent and warmed, if necessary, whereupon the moving muscles will work down said

edge to the proper size and symmetrical shape.

55 In the muscle self-trimming and self-shaping process, just described, an integral handle to the tray is an insurmountable hindrance because it prevents the closing of the jaws and the natural movements of the 60 mouth. I have, therefore, invented a tray with a detachable handle which can be readily removed from the tray during the 65 essential action of the lips and cheeks which has been explained.

The invention also consists in the features of construction and combinations of parts hereinafter described and specified in the 70 claims.

A further use of my invention is to permit 75 the removal of the handle from the tray when the latter is used as bite-plates in taking so-called "bites" for articulation in making artificial teeth. This is a great improvement over the methods now in common 80 use which cannot be practiced with trays having fixed handles.

In the accompanying drawings illustrating the preferred embodiments of my invention: Figure 1 is a side elevation of a 85 tray for taking an impression of the lower jaw, showing one form of detachable handle. Fig. 2 is an under plan view. Fig. 3 is a front elevation of the tray with the handle removed. Fig. 4 is a detailed view of the 90 handle. Fig. 5 is an under plan view of a similar tray equipped with a modified form of detachable handle. Fig. 6 is a sectional view on the line 6—6 of Fig. 5, Fig. 7 is a detailed view of the modified form of handle. Fig. 8 is an under plan view of a tray 95 for taking an impression of the upper jaw, and Fig. 9 is a sectional view of the latter with impression material thereon.

Referring first to Figs. 1 to 4 inclusive of 100 the drawings, 1 designates the tray which is similar to the low-rimmed dental trays in common use. A slight enlargement or projecting lug 2 is arranged at the middle of the convex face of the tray. Said lug is 105 preferably formed integral with the tray, as here shown, but it may be made separate and secured at the desired point in any suitable manner, such as by rivets 2^x in Fig. 8. A slot 3 extends through said lug to receive 110 the end 4 of the detachable handle 5. Said

handle is stepped, as at 6, so as to bring the finger portion 7 away from the lip when the handle is engaged with the tray for putting the latter in place or removing it from the mouth.

In the modified construction illustrated in Figs. 5 to 7 inclusive, the tray 1^a is provided with a projecting lug 2^a similar to that already described except that instead of a single slot it is provided with two parallel slots 3^a having projecting pins 3^b arranged therein on the internal surfaces thereof which are farthest away from one another. The handle 5^a in this instance is made of a piece of bent resilient wire having its extremities 4^a notched at 4^b to engage the pins 3^b when the handle is attached to the tray, for preventing said handle from dropping out. This handle is stepped, at 6^a, and is provided with the finger portion 7^a so that it conforms generally to the shape of the handle 5 described in connection with Figs. 1 to 4 of the drawing.

I do not limit myself to the exact constructions shown and described herein but reserve the right to make such changes as fairly fall within the scope of the appended claims. For instance, any other suitable

method of connecting the detachable handle to the tray may be employed instead of the one I have explained.

I claim:—

1. A dental impression tray having a detachable handle.

2. An impression tray for dentistry provided with a socket and a handle detachably engaging said socket.

3. A dental impression tray having two parallel slots therein, and a detachable handle comprising a bent piece of resilient wire, the ends of which are adapted to be inserted into said slots in the tray.

4. A dental impression tray having two parallel slots therein, pins in said slots, and a detachable handle comprising a bent piece of resilient wire, the ends of which are adapted to be inserted into slots in the tray and are notched to engage said pieces for the purpose specified.

In testimony whereof, I affix my signature, in presence of two witnesses.

JACOB W. GREENE.
